CLAIM

The ornamental design for a tire, as shown and described.

DESCRIPTION

FIG. 1 is a perspective view of the tire;

FIG. 2 is a front elevation view of the tire;

FIG. 3 is side plan view of the tire;

FIG. 4 is a partial top plan view of the tire; and,

FIG. 5 is an enlarged perspective view of the tire.

In the drawings, the broken lines depict portions of the tire that form no part of claimed design.
